UNITED STATES PATENT OFFICE.

THOMAS WILLIAM BYRNE AND ROBERT CHRISTOPHER LEHANE, OF BOSTON, MASSACHUSETTS, ASSIGNORS TO THE BRYANT ELECTRIC COMPANY, OF BRIDGEPORT, CONNECTICUT, A CORPORATION OF CONNECTICUT.

PANEL-BOARD FITTING.

1,195,778.

Specification of Letters Patent. Patented Aug. 22, 1916.

Application filed February 9, 1914. Serial No. 817,622.

To all whom it may concern:

We it known that we, THOMAS W. BYRNE and ROBERT CHRISTOPHER LEHANE, both citizens of the United States of America, residing in the city of Boston, county of Suffolk, and State of Massachusetts, have invented certain new and useful Improvements in Panel-Board Fittings, of which the following is a specification.

10 The present invention relates to panel board fittings, and the object of our present invention is to provide for electrical units adapted to be combined in a panel board installation an individual cover for each unit, 15 the cover being of such construction that upon the assembly of the fittings upon the panel board the covers form a practically unbroken protection coextensive with the installation and serving to shield the units 20 against mechanical injury and accidental electrical contact.

In the accompanying drawings, Figure 1 is a plan view of a panel board installation in which several fused switch fittings are 25 employed, some of which are provided with our improved cover; Fig. 2 is a longitudinal section through one of the fittings showing our cover in position thereon; Fig. 3 is an end elevation of two fittings showing 30 covers thereon; Fig. 4 is a perspective of the cover alone; Fig. 5 is a view similar to Fig. 1, but showing a fitting of different type with a modified cover thereon; Fig. 6 is a longitudinal section therethrough; Fig. 35 7 is an end elevation of two fittings with covers in position; Fig. 8 is a perspective of the cover plate alone; and Fig. 9 is a similar view showing a cover of this modified construction adapted for the switched fitting 40 shown in Figs. 1 to 4.

The panel board unit shown in Figs. 1 to 4 for which the present cover plate is designed, is of common type comprising a base 10 of porcelain or other insulating material, 45 centrally grooved at 11 on its upper face for the reception of the mains 12, and provided at each end with terminals 13 for the branch wires 14. Electrical connection between the terminals 13 and the mains 12 is established 50 through the switch 15 and the fuse plugs 16 in well understood manner.

Substantially coextensive with the base and resting upon its upper face, we provide a cover plate 17 of any suitable material,

but here shown of a mechanically strong insulating material such as "composition" or "condensite". Apertures 18 are formed therein in register with the fuse plug receptacles 19 on the base, to permit the insertion of the entering end of the fuse plug 16, but 60 of less diameter than the head of a standard plug. Apertures 20 are also formed to permit the passage therethrough of the operating stem 21 of the switch. The switch handle 22, which is threaded down on the spindle 21, engages and serves to hold the cover in position with precision. An aperture 23 is also preferably formed through which the switch indicators 24 may be observed. Also adjacent the switch handle, and here shown 65 on the opposite side thereof, is formed an elongated aperture 25 through which may be observed a strip of celluloid or paper slipped between the cover and the base and on which is printed or written the location 70 of the circuit which this switch controls. One of the longitudinal edges of each cover plate may be shaped in any suitable manner to form a joint with the adjacent cover plate in assembled position. As here shown, 75 one edge is formed with a raised flange 26. In assembled position on the panel board, the flange 26 of one plate overlies the edge of the adjacent plate. To aid in positioning the cover on the base 10, we provide on 80 its lower face studs 27 (Fig. 2) which take into recesses 28 in the upper face of the base. As here shown these recesses are the usual ones for the reception of the heads of 85 securing screws by means of which the fitting is mounted upon the panel board.

In Figs. 5 to 8 we have shown a modified construction of cover applied to a fused, but switchless, fitting. The base 29 of this fitting is also transversely grooved at 30 for 90 the reception of line wires while the connection therefrom to the branch wire terminals 31 is made through the fuse plugs 32 inserted in the receptacles 33 therefor on the base.

The cover, in the modified form here shown, comprises a metal plate 34 substantially coextensive in area with the base and apertured at 35 in register with the fuse plug receptacles. One longitudinal edge of 105 the plate is provided with a raised flange 36 and the opposite edge with a bead 37. In juxtaposed position on the panel board the

flange 36 of one cover forms a lap joint with the bead 37 of the adjacent cover. To insulate the cover from any electrically live elements on the base, a sheet of fiber 38 or 5 the like is secured to the lower face of the plate, preferably by rivets 39. Since, in a fitting of this type, there is no switch stem to pass through the plate and accurately position it on the base nor any switch handle 10 to hold the cover in place when the fuses are out, it is desirable to provide some means for holding the cover on the base. For this purpose we have provided a pair of screws 40 passing down through the cover and 15 taking into threaded sockets 41 carried by the base.

In Fig. 9 we have shown a cover plate 42 of this type but adapted for the switched fitting shown in Figs. 1 to 4. The plate is 20 apertured in like manner as the plate there shown, but is provided with bosses 43 around the holes 44 for the switch stem. Space is also left between the insulation 45 and the plate 42 for the insertion of celluloid or 25 paper strips 46 which carry a legend showing the direction of the circuit controlled by the switch. As in the first mentioned construction, the cover is located in position by the switch stems and is held on by 30 the switch handles when the fuse plugs are out.

When a series of fittings of either type shown, or of other types to which the invention is applicable, are assembled upon a 35 panel board, it is obvious that the several cover plates form a substantially continuous and unbroken shield which effectually protects the fittings from mechanical injury as well as preventing electrical contact with 40 the conductors thereon. Various modifications of detail of construction and shape will readily suggest themselves and we do not

limit our invention to the precise constructions shown.

We claim as our invention:—

1. For use on a panel board fitting of the type described, a metallic cover plate substantially coextensive in area with the fitting which it is designed to cover, a sheet of insulation lining said plate, said plate and 50 lining being perforated in register to permit the passage of a switch stem therethrough, and the plate being slotted adjacent said switch stem aperture to form a sight aperture for a switch indicating legend 55 carrier adapted to be inserted between said plate and lining at the slot, substantially as described.

2. As a new article of manufacture for electric fittings of the type described, an 60 insulating cover plate comprising a sheet of metal, substantially coextensive in area with the fitting which it is designed to cover, a sheet of insulation lining said plate, said plate and lining being perforated in register 65 to permit the passage of fuses therethrough, together with registering apertures in the plate and lining between the opposite ends of the plate and the fuse apertures to permit the passage of switch actuating means 70 therethrough, an aperture in the cover plate adjacent the switch stem and a legend strip insertible between said plate and lining to position beneath said aperture and on which the direction of the circuit controlled may 75 be indicated.

In testimony whereof we have signed our names to this specification, in the presence of two subscribing witnesses.

THOMAS WILLIAM BYRNE.

ROBERT CHRISTOPHER LEHANE.
